(57) **CLAIM**

The ornamental design for a pumps for pharmaceutical and cosmetics products, as shown and described.

DESCRIPTION

FIG. 1 is a perspective view of the pumps for pharmaceutical and cosmetics products.

FIG. 2 is a front view thereof.

FIG. 3 is a back view thereof.

FIG. 4 is a side view thereof.

FIG. 5 is the other side view thereof.

FIG. 6 is a bottom view thereof; and,

FIG. 7 is a top view thereof.

The broken line showing of a rectangle on the front of the article represents an internal boundary with the line itself and the area within forming no part of the claimed design.
